UNITED STATES PATENT OFFICE.

WILLIAM C. STEWART, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

SOLE-EVENING MACHINE.

1,412,070.

Specification of Letters Patent. Patented Apr. 11, 1922.

Application filed May 15, 1919. Serial No. 297,256.

To all whom it may concern:

Be it known that I, WILLIAM C. STEWART, a subject of the King of England, residing at Swampscott, in the county of Essex and State of Massachusetts, have invented certain Improvements in Sole-Evening Machines, of which the following description, in connection with the accompanying drawings, is a specification, like reference characters on the drawings indicating like parts in the several figures.

This invention relates to splitting machines and is herein illustrated as embodied in a machine designed for evening sole blanks which are to be used in the manufacture of boots and shoes.

Machines have been used for this purpose in which the splitting mechanism is automatically set in accordance with the thickness of a selected locality of the blank; and the illustrative machine is of this general type. Hitherto it has been customary to provide two separable members such as rolls between which the blank is fed to a knife, and to control the thickness to which the blank is split by adjustable stops, the position of the stops being responsive to the thickness of the blank and serving to determine or limit the extent of separating movement of one of the rolls. The mechanism for adjusting or setting these stops and for resetting them after each blank has been split is more or less complicated; and one object of the present invention is to provide a simplified mechanism for limiting the extent of movement of one of these separable members.

According to one feature of the present invention the stops are obviated, and one of the separable members is locked at the proper time from movement in either direction. In the illustrative machine the blank is advanced between a gage roll and a feed roll to the knife, said rolls being separable as is usual; and the gage roll, when it has been moved by the blank the proper distance away from the knife and feed roll, is locked from further bodily movement and remains so locked until the blank has been split.

With the upper or gage roll thus locked it may happen that a locality in the blank will be encountered which is so thin that the blank will not be fed; and in order to provide for such an occurrence another feature of the invention relates to means for causing

the feed roll to rise, when permitted to do so by a thin locality of the kind referred to, and press the blank against the gage roll. In the illustrative machine the feed roll is provided with two spring supports, one being operative at all times and the other being operative only after the feed roll has been depressed a predetermined distance. The latter support is the one which is effective when the blank is being split, and the former is provided to take care of the very thin localities of the blank.

It is desirable that the operator should know the thickness of the finished blanks as fast as they are split so that he may sort them into groups the members of which have the same thickness. Visual indicators for apprising the operator of the thickness of the finished blank have been employed, but hitherto such indicators have been automatically reset to normal initial position as soon as the blank has been split. As a result, the operator frequently fails to read the indicator correctly or forgets the reading and is obliged either to sort the finished blank incorrectly or to take time to measure the blank with a gage. According to another feature of the invention the indicator, after having been set by a blank, is held set or locked until a succeeding blank is fed to the machine. With such a construction the reading of the indicator is preserved so that it may be seen at any time prior to the presentation of the next blank; and the operator is not compelled to rely upon a reading which is momentary or of short duration.

These and other features of the invention, including certain details of construction and combinations of parts, will be described as embodied in an illustrative machine and pointed out in the appended claims.

Referring now to the accompanying drawings,—

Fig. 1 is a side elevation of a machine in which the present invention is embodied;

Fig. 2 is a front elevation of the machine;

Fig. 3 is a plan of the machine;

Fig. 4 is a detail in section showing more particularly the relation to the feed and gage rolls of the movable members which control the gage roll locking mechanism and the operation of the indicator;

Fig. 5 is a detail in longitudinal vertical section of part of the locking mechanism;

Fig. 6 is a detail in horizontal section of part of the locking mechanism;

Fig. 7 is a detail in transverse vertical section of part of the locking mechanism;

5 Fig. 8 is a detail in transverse vertical section of part of the indicating mechanism;

Fig. 9 is a side elevation of the indicator;

10 Fig. 10 is a transverse vertical section of the indicator, and

Fig. 11 is a detail in longitudinal vertical section showing the rack and pinion for turning the indicator wheel.

15 Before proceeding to a detail description of the machine, a brief outline of its mode of operation will be given in connection with Fig. 4. The feed and gage rolls 15, 43 are normally close together and are continuously driven. Just in the rear of the 20 bite of the rolls is a stationary splitting knife 41. Just in front of the bite of the rolls is the forward edge of an actuator 121 which controls the dogs by which the gage roll is to be locked in automatically adjusted position. Farther in front of the bite 25 of the rolls is one end of a pivoted lever 151 which controls the locking and unlocking of the indicator. Normally the indicator is locked in position to indicate the thickness of the forward end of the sole which has previously passed through the machine, and the locking dogs by which the upper or gage roll is to be locked in adjusted position are held in inoperative position. When, now, a blank is presented to 30 the machine it raises the lever 151 to unlock the indicator, moves the actuator 121 to release the locking dogs and raises the gage roll 43. The raising of this roll turns the indicator to expose to view the proper numeral, the released dogs lock the gage roll from movement, and the blank is split by passing through the machine. As the 35 rear end of the blank passes from beneath the actuator 121 the dogs are once more moved into inoperative position but the indicator remains locked until the next blank is presented to the machine and lifts the forward end of the lever 151.

40 Referring now more particularly to Figs. 1, 2 and 3, the shaft 13 of the lower or feed roll 15 is rotatably mounted in bearings carried at the ends of arms 17 which are pivoted about the axis of studs 19 carried by the 45 frame 21 of the machine. The bearings of this roll are normally held up against adjustable stop-screws 23 by round-headed pins 25 the stems of which are received in sockets in cylindrical supports 27, said supports having at their lower ends integral collars between which and the heads of the pins are located comparatively light coiled springs 29. Set screws 31 threaded through flanges on the frame furnish means for raising and lowering the supports 27 to vary 50

the tension of the springs 29. The principal purpose of these light springs 29 is to hold the lower roll normally in the position shown, to permit it readily to be depressed when a blank is presented to the machine 70 and to raise the roll if there occurs in the blank a spot so thin that otherwise the blank would not be properly fed.

55 Located in the rear of the round-headed pins 25 are round-headed pins 33 which are threaded through cylindrical supports 35, said supports being vertically slidable through smooth bores in flanges of the frame 21. Heavy coiled springs 37 tend at all times to hold these supports as shown in 80 their uppermost positions, such positions being determined by nuts 39 threaded upon the lower ends of the supports 35. As has been stated, the light springs 29 normally hold the bearings of the lower roll up 85 against the stop-screws 23. In this position of parts the upper element of the roll is in substantially the same horizontal plane which contains the edge of the knife 41 (see Fig. 4). If a skiving is to be removed from 90 a blank, the lower roll must be depressed to provide space for the skiving to pass beneath the knife. In the present machine the lower roll is depressed by the entrance of the forward end of the blank between 95 the rolls, and the amount it will be depressed before the upper or gage roll 43 is raised is determined by the positions of the round-headed pins 33. In order to permit simultaneous and equal vertical adjustment of these pins in their supports 35, there are 100 slidably keyed on the lower ends of the stems of the pins gears 45, the stems having keyways 47 into which extend keys 49 which are fast to the gears. A rack-bar 51, horizontally slidable in the frame of the machine, meshes with these gears and may be moved in one direction or the other by manipulating the handle 53 of a bar 55 which is pivoted at 57 to the frame of the machine 105 and has a slot 59 to receive a pin 61 carried by the rack bar. In order to hold the bar 55 in adjusted position and at the same time to permit it to be manipulated when desired, a spring-pressed detent 63 carried by the 110 bar, engages a ratchet segment 65 carried by the frame of the machine. With this construction, swinging of the handle 53 in one direction or the other will rotate the gears 45 to raise or lower the headed pins 115 33 so as to vary the space between their heads and the spherical sockets with which these heads contact. The distance from the heads to the sockets determines the extent to which the lower roll will be depressed 120 before the upper roll is raised and locked, as will presently be described. This distance also determines the thickness of the skiving which will be removed from a blank 125 of uniform thickness. If the blank has 130

thick spots, the springs 37 will yield as in an ordinary splitting machine.

The bearings of the upper roll are formed in a forked casting 67 pivoted about a fixed 5 rod 69 and having a tail provided at its end with a spherical socket to receive a button 71. A similar button 73 is located in a socket in the frame of the machine; and a coiled spring 75 is located between the 10 buttons, an adjusting screw 77 furnishing means for varying the tension of the spring. This spring tends to rock the casting 67 about its pivot 69 in a counter-clockwise direction, as viewed in Fig. 1, to cause 15 the upper roll 43 to approach the lower roll 15 and is limited in this movement by a set screw 79 which engages a lug on the member 67. This screw is set so that normally the upper roll is close to the lower roll.

20 As has been explained above, the entrance of the forward end of a blank between the rolls depresses the lower roll a slight distance, determined by the positions of the headed pins 33, and raises the upper roll, 25 said upper roll being automatically locked from further bodily movement before the forward end of the blank reaches the knife and remaining so locked while the blank is being split. Referring now more particularly to Figs. 1, 5, 6 and 7, there is attached 30 by a link 81 to the lower end of the casting 67, which carries the bearings in which the shaft 83 of the gage roll is mounted; a bell crank lever 85 pivoted at 87 to the frame of the machine. This lever at the end of its horizontal arm is provided with a slot to receive a roll 89 on a pin 90 which is driven into the lower end of a toothed bar 91, the bar being vertically slidable in bearings in 35 the frame of the machine. Consequently when the forward end of a blank enters between the rolls 15, 43 and the upper roll is raised, the toothed bar 91 is also raised. In order to lock this bar and thereby the roll 40 in raised position a plurality of dogs 93 are mounted one on top of another in a suitable guideway rigid with the frame of the machine, the purpose of using a plurality of dogs instead of one being to obviate the 45 necessity of providing fine teeth on the bar 91. Each dog has a slot 95 extending into the side thereof and a socket leading out of the slot; and each socket receives a coiled spring 96, one end of which abuts against 50 the bottom of the socket and the other end against a flange 97 formed on a short link 99 which is mounted on pivots 101, 103 carried by arms 105, 107, said arms being pivoted at 109 and 111 respectively to the casting 55 67. As long as the link 99 is held to the left, as shown in Figs. 1 and 6, the flange 97 holds all of the dogs 93 out of engagement with the toothed locking bar 91; but, as soon as the link is moved to the right, the 60 dogs are all urged yieldingly into contact with the bar 91, and one of the dogs will engage the bar and lock it from movement, thereby also locking the gage roll 43 from further movement toward or away from the feed roll 15. In order to hold the link 99 65 normally in the position shown in Figs. 1 and 6, a coiled spring 113 is connected at one end to a pin formed upon an extension of the arm 107 and at the other end to a small rod 115 which is slidable in a lug 70 formed on the casting 67 and has threaded upon it two adjusting nuts 117. In order to move the link 99, said link has an up-standing lug 199 (see Fig. 1) the curved 75 forward face of which is located a little in the rear of the gage roll in position to be engaged by a roll (see Fig. 6) which rotates about the axis of a screw 119. The screw is carried by an actuator 121 in the general 80 form of a curved bar which is journaled at each end on bearings which are concentric with those of the gage roll. A tension spring 123, fastened at one end to a pin on the actuator and at the other end to a pin on the frame of the machine tends at 85 all times to swing the actuator into and hold it in the position shown against a stop, not shown, with its forward edge located just in front of the bite of the rolls. The curve of the operative face of the lug 199 is such 90 that, as soon as the forward end of a blank has separated the rolls and been firmly gripped by the bite thereof, the movement of the actuator due to the push exerted upon it by the blank swings the link 99 to the 95 right; and the dogs 93 are released and caused to lock the bar 91 from further movement during the splitting of the blank. As soon as the rear end of the finished blank passes from beneath the actuator 121, the 100 spring 123 returns the actuator to its normal position and permits the spring 113 to move the dogs 93 to inoperative position.

105 The operator stands at the left side of the machine, as viewed in Fig. 3, feeds the blanks one by one to the machine with his right hand and removes the finished blanks from the machine with his left hand. As fast as the blanks are split, they should be sorted into groups in accordance with their 110 thicknesses. In order to apprise the operator of the thicknesses of the finished blanks, an indicator the casing of which is shown at 115 125 is provided, there being an opening in the casing to expose the proper one of a plurality of numerals which are formed upon the periphery of a wheel located inside the casing. In the illustrative machine, which is designed for splitting sole blanks, these numerals represent "irons", an 120 iron being one forty-eighth of an inch. In Fig. 3, the numeral 0 is exposed since there is no blank in the machine.

125 Referring now more particularly to Figs. 8 to 11 with occasional references to Figs. 130

1 and 3, the casing 125 is fastened to the frame of the machine and carries a rotary shaft 127 to which the indicating wheel 129 is fast. A pinion 131, fast to the shaft, meshes with a rack formed upon the upper end of a rack bar 133 the lower end of which (see Fig. 1) rests upon the head of a screw 135 threaded into the upper end of the locking-bar 91 and held in adjusted position by a check-nut 137. Consequently, when the locking bar is moved upwardly the rack-bar 133 moves with it and turns the wheel 129, the parts being so constructed and arranged that the number which is exposed at any time represents in irons the distance between the gage roll 43 and the edge of the knife 41. A spring 139 continually presses upon the top of the rack-bar 133 to urge it down into contact with the top of the screw 135 which is rigid with and in effect part of the locking bar 91. After the proper numeral has been exposed, it is desirable that it be held in exposed position until the next blank is presented to the machine so that the operator may not lose track of the measurement of the sole which is being or has been split. To this end a ratchet wheel 141, fast to the shaft 127, is arranged to be engaged and locked by a pawl 143. This pawl is fast inside the casing 125 to the inner end of a small rock-shaft 145 which has a bearing in a boss on the side of the casing 125. At the outer end of the rock-shaft one end of an arm 147 is clamped, the other end having a downwardly facing spherical socket to receive the rounded upper end of a rod 149. The lower end of this rod is also rounded and is received in a spherical socket at one end of a lever 151 which is pivoted at 153 to the frame of the machine. A tension spring 155 connects the arm 147 with the lever 151 and tends at all times to hold the rod 149 in its upper and lower sockets. The weight of that portion of the lever 151 which is to the left of the pivot 153, as viewed in Fig. 1, tends always to hold the parts in the positions shown with the pawl 143 in engagement with the ratchet 141. As viewed in Fig. 9, the wheel may be turned in a counterclockwise direction but is held from turning in the opposite direction until the lever 151 is swung in a direction to release the pawl. The lever 151 extends 55 toward the front of the machine through a groove in the lower roll 15 and is bent upwardly in front of the bite of the rolls. As soon, therefore, as a blank is fed over the table 153 to the machine, the forward end of the lever 151 is raised and the ratchet wheel 141 released, whereupon the spring 139 returns it to normal position in which the numeral zero is exposed to view.

The rotation of the rolls 15 and 43 is controlled by tight and loose pulleys 157,

159 from one to the other of which a belt may be shifted by manipulating a handle 161 to reciprocate a slide rod 163 to one end of which the belt-engaging member 165 is attached. The pulleys are mounted on a drive shaft 167 having fast thereon a pinion 169 which meshes with a large gear 171 fast to the shaft 13 of the lower or feed roll. The left-hand end of this shaft, as viewed in Fig. 2, is connected by an Oldham coupling 173 with a small gear 175 which is rotatable on a stub shaft carried by a rigid part of the machine. The gear 175 meshes with a gear 177 which is fast to the shaft of the upper roll. The table 153 at the front of the machine is provided with the usual upstanding side flanges 181.

Although the invention has been set forth as embodied in a machine for splitting blanks, it should be understood that the invention is not limited in the scope of its application to the particular machine which has been shown and described.

Having thus described my invention, what I claim as new and desire to secure by Letters Patent of the United States is:

1. A machine of the class described, having in combination, an operating tool, a pair of members located in front of the tool and adapted to receive the work between them, said members being normally movable toward and from each other, and means operated by the work for locking one of the members from movement in either direction. 100

2. A machine of the class described, having, in combination, an operating tool, a pair of members located in front of the tool and adapted to receive the work between them, said members being normally movable toward and from each other, and means operated by the work between the time the forward end of the work is received between the members and the time said end reaches the tool for locking one of the members from movement in either direction. 105

3. A machine of the class described, having in combination, a knife, a feed roll and a gage roll located in front of the knife, the mounting of the rolls being such that entrance of a piece of work between the rolls separates them, and means operated by the work for locking the gage roll from movement toward or from the feed roll 115 during the splitting operation.

4. A machine of the class described, having, in combination, a knife, a feed roll and a gage roll located in front of the knife, the mounting of the rolls being such that entrance of a piece of work between the rolls separates them, means operated by the work for locking the gage roll from movement toward or from the feed roll 125 during the splitting operation, and means respon- 130

- 5 sive to the passing of the work from between the rolls for unlocking the gage roll.

5 6. A machine of the class described, having in combination, a knife, a pair of rolls located in front of the knife the mounting of the rolls being such that entrance of a piece of work between the rolls separates them, a toothed member connected with one of the rolls to move with it, a plurality of dogs normally held out of engagement with the teeth, and means responsive to the entrance of a piece of work between the rolls for moving the dogs toward the toothed member to lock it from movement.

10 7. A machine of the class described, having in combination, a knife, a pair of rolls located in front of the knife the mounting of the rolls being such that entrance of a piece of work between the rolls separates them, a toothed member connected with one of the rolls to move with it, a plurality of dogs normally held out of engagement with the teeth, means responsive to the entrance of a piece of work between the rolls for moving the dogs toward the toothed member to lock it from movement, and means responsive to the passing of the finished work from between the rolls for withdrawing the dogs.

15 8. A machine of the class described, having, in combination, an operating tool, a pair of members located in front of the tool and adapted to be separated by receiving the work between them, means for arresting the separating movement of one of the members preparatory to the operation of the tool, and a movable member located adjacent to and in front of the tool in position to be engaged and moved by the work for controlling the operation of the arresting means.

20 9. A machine of the class described, having in combination, an operating tool, a pair of members located in front of the tool and adapted to be separated by receiving the work between them, means for arresting the separating movement of one of the members preparatory to the operation of the tool, and a movable member located adjacent to and in front of the tool in position to be engaged and moved by the work for controlling the operation of the arresting means.

25 10. A machine of the class described, having in combination, a knife, a pair of separable feed rolls for advancing the work to the knife, means for limiting the extent of separation of the rolls, and a movable member located between the rolls in front of the knife in the path of the work for controlling the operation of the limiting means.

30 11. A machine of the class described, having in combination, a knife, a pair of separable feed rolls for advancing the work to the knife, means for limiting the extent of separation of the rolls, a movable member located in front of the knife and adapted to be moved in one direction by engagement with the work to render the limiting means operative and to be moved in another direction when the work passes from beneath it to render the limiting means inoperative.

35 12. A machine of the class described, having in combination, a knife, a gage roll and a feed roll located in front of the knife and adapted to be separated by entrance of the work between them, a toothed member connected with one of said rolls in such manner as to be compelled at all times to move with it, a dog arranged to be engaged with and disengaged from the toothed member, means for normally holding the dog out of engagement with the toothed member, and means operated by engagement with the work as it passes through the machine for moving the dog into engagement with the toothed member.

40 13. A machine of the class described, having in combination, a knife, a gage roll, a feed roll, means for limiting the extent of movement of the gage roll away from the knife, and two spring supports for the feed roll, one being operative at all times and the other being operative only after the feed roll has been moved a predetermined distance away from the knife.

45 14. A machine of the class described, having in combination, a knife, a gage roll, a feed roll, means for limiting the extent of movement of the gage roll away from the knife, two spring supports for the feed roll, one being operative at all times and the other being operative only after the feed roll has been moved a predetermined distance away from the knife, and means whereby the last-named support may be adjusted to vary the predetermined distance.

50 15. A machine of the class described, having in combination, a knife, a pair of rolls for feeding the work to the knife, means for limiting the movement of one roll away from the other, means for limiting the movement

of the other roll toward the first, yielding means acting at all times to urge said other roll to the limit of its movement of approach, and a spring sustained support for said other roll normally inoperative but located to become operative when said other roll has been moved a predetermined distance away from the first roll.

16. A machine of the class described, having in combination, a knife, a pair of rolls for feeding the work to the knife, means for limiting the movement of one roll away from the other, means for limiting the movement of the other roll toward the first, yielding means acting at all times to urge said other roll to the limit of its movement of approach, a spring sustained support for said other roll normally inoperative but located to become operative when said other roll has been moved a predetermined distance away from the first roll, and means whereby the support may be adjusted to vary the predetermined distance.

17. A machine of the class described, having in combination, a knife, a gage roll, and a feed roll for advancing work to the knife, carriers for the rolls, means for limiting the extent of movement of the gage roll away from the feed roll, a stop for limiting the approach of the feed roll to the gage, yielding means acting at all times to urge the feed roll carrier toward the stop and normally holding the carrier against the stop, a support for the feed roll normally spaced from the feed roll carrier but adapted to engage the carrier when said carrier is moved a predetermined distance away from the stop, and a comparatively heavy spring for sustaining the support.

40 18. A machine of the class described, having in combination, a knife, a gage roll and a feed roll for advancing work to the knife, carriers for the rolls, means for limiting the extent of movement of the gage roll away from the feed roll, a stop for limiting the approach of the feed roll to the gage roll, yielding means acting at all times to urge the feed roll carrier toward the stop and normally holding the carrier against the stop, a support for the feed roll normally spaced from the feed roll carrier but adapted to engage the carrier when said carrier is moved a predetermined distance away from the stop, a comparatively heavy spring for sustaining the support, and means whereby the support may be adjusted to vary the predetermined distance.

19. A machine of the class described, having in combination, a knife, a gage roll and a feed roll located in front of the knife, yielding means for urging the gage roll toward the feed roll, yielding means of less strength than the gage-roll-yielding means for urging the feed roll toward the gage roll, a support for the feed roll arranged to

become operative when the feed roll has been moved a predetermined distance away from the gage roll, and a comparatively strong yielding means for sustaining the support.

20. A machine of the class described, having in combination, separable gage and feed rolls, a knife to which the work is advanced by the rolls, means operated by the work for moving the gage roll to and locking it in adjusted position, a yielding support for the feed roll arranged to become operative only after said roll has been moved a predetermined distance away from the knife, and means for moving the feed roll toward the knife and away from the support when a sufficiently thin locality in the work is encountered.

21. A machine for operating upon a blank and for indicating the degree of a selected characteristic, having in combination, operating mechanism including a movable member, an indicator, means responsive to the movement of the member for setting the indicator, means for holding the indicator so set, and means adapted to be operated by the presentation to the machine of a succeeding blank for releasing the indicator.

22. A machine for splitting a blank and for indicating the thickness to which it is split, having in combination, splitting mechanism, an indicator, feeding mechanism, means responsive to the action of the blank upon the feeding mechanism for setting the indicator, means for holding the indicator in its set position, and a member located in front of the feeding means movement of which releases the holding means.

23. A machine for reducing a blank as to a selected dimension and for indicating the extent of the dimension, having in combination, a pair of separable members between which the blank is fed, an indicator, means responsive to the separation of the members for setting the indicator, means for holding the indicator set, and means responsive to the presentation of a succeeding blank to the separable members for releasing the indicator.

24. A machine of the class described, having in combination, a tool, means for feeding a blank past the tool to permit it to be operated upon, an indicator, means operated by presentation of a blank to the machine for setting the indicator to indicate the degree of a selected characteristic of the blank, and means for holding the indicator so set until the next blank is presented to the machine.

25. A machine of the class described, having in combination, splitting mechanism, an indicator, means for setting the indicator to indicate the thickness to which the blank is split, and means for holding the indicator in its set position until another blank is presented to the machine.

26. A machine of the class described, hav-

ing in combination, a knife, a gage roll, a feed roll, means for limiting the extent of movement of the gage roll away from the knife, and two supports for the feed roll, 5 one being operative at all times and the other being operative only after the feed roll has been moved a predetermined distance away from the knife.

27. A machine of the class described, having in combination, a knife, a gage roll, a

feed roll, means for locking the gage roll from movement toward or from the knife, and means for causing a blank to be engaged by the rolls when a locality is encountered in the blank which is too thin to be split as 15 well as when thicker localities are encountered.

In testimony whereof I have signed my name to this specification.

WILLIAM C. STEWART.
